ELECTROMAGNETIC RELAY

Martin L. Nelson, Park Ridge, Ill., assignor to
 Associated Electric Laboratories, Inc., Chicago,
 Ill., a corporation of Delaware

Application January 27, 1941, Serial No. 376,150

6 Claims. (Cl. 200—37)

The present invention relates to relays and more in particular to electro-magnetic switching relays.

The main object of the present invention is the provision of an improved electro-magnetic relay which is light in weight, rugged and economical in construction, and reliable and positive in operation.

A further object of the invention is the provision of a relay structure that has a maximum current drain of less than twenty milliamperes and a maximum weight of less than sixty grams.

A still further object of the invention is the provision of a relay structure having minimum over-all dimensions in order to reduce the amount of space required for the mounting while still maintaining an efficient magnetic circuit to permit a margin of safety for operation on extremely low voltages.

A still further object of the invention is the provision of a new and improved contact spring structure including a removably mounted armature.

One of the important applications of the electro-magnetic relay of the present invention is in the relay equipment of the instrument carried by the balloon which is used in radio-sonde (sounding) by the meteorological service of the Weather Bureau. In order to obtain weather data, a balloon carried instrument is released and as it ascends it automatically transmits radio signals regarding weather conditions, which signals are received and recorded at the ground-station.

There are three problems which enter into radio-sonde. The first is that it is important to keep the cost of the balloon carried instrument to a minimum because it is used but once. The second is that the weight of the instrument must be kept to a minimum in order to attain the maximum altitude with the balloon. The third is that the balloon carried instrument must be highly efficient because it requires high rates of response so that the time for a complete sounding may be kept within practical limits. It will be seen that the electro-magnetic relay of the present invention is a contributing factor in overcoming the above problems in radio-sonde.

Other objects and advantages of the present invention will be apparent by reference to the following specification taken in connection with the accompanying drawing, in which:

Fig. 1 is a top plan view of an electro-magnetic relay constructed and arranged in accordance with the present invention.

Fig. 2 is a view in front elevation of the electro-magnetic relay shown in Fig. 1.

Fig. 3 is a right end elevation view of the electro-magnetic relay shown in Fig. 1.

Fig. 4 is a left end elevation view of the electro-magnetic relay shown in Fig. 1.

Fig. 5 is an exploded perspective view of one of the pole pieces, the armature, and the restoring spring for the armature.

10 The electro-magnetic relay shown in the drawing comprises a base member 10 of insulating material upon which the L-shaped heel or pole pieces 11 and 12 of iron or magnetic material are mounted. Supported between the pole pieces 11 and 12 is the coil 13. The armature 14 is pivoted on one of the pole pieces and is provided with a spring member 19 for restoring the armature and for maintaining it in pivotal relation with the pole piece as will be described more in detail hereinafter. The circuit controlling contact members 16, 17 and 18, which cooperate with the spring 19, are also secured to the base member 10 in a manner to be described hereinafter.

20 25 The coil 13 contains a core 20 of magnetic material which is reduced in size at each end thereof and inserted into holes provided therefor in the pole pieces 11 and 12. The core 20 is secured to the pole pieces 11 and 12 by flaring over the ends 21 and 22 of the core or by ring staking. However, any other method of fastening the core 20 and the pole pieces 11 and 12 may be used, for example, by tapping the core 20 at each end and inserting screws through the holes in the pole pieces 11 and 12 into the tapped holes in the core. The coil wiring terminals 23 and 24 which are secured to the coil spool head 25, are insulated from the winding of the coil 13 by a thin insulating washer 26. Another insulating washer is also placed between the pole piece 11 and the coil spool head 25.

30 35 40 In order to secure the assembly comprising the coil 13 and the pole pieces 11 and 12, to the base member 10, lugs 31 and 32 on the pole piece 11 and lugs 33 and 34 on the pole piece 12 (see Figs. 3 and 4) are provided. The base member 10 is provided with slotted holes therein to receive the lug portions of the pole pieces 11 and 12. The lugs extend through and beyond the under surface of the base and are flared out or staked to thereby secure the assembly to the base member.

45 50 55 The pole piece 11 is notched to provide lugs 28 and 29 which freely enter notches 41 and 42, respectively, in the armature 14 (see Fig. 5) in

order to provide a loose pivotal mounting for the armature. This arrangement also prevents relative displacement between the armature and the pole piece 11 except in a direction perpendicular to the plane of the armature. In order to give the armature 14 a normal bias away from other pole piece 12 and to maintain the armature 14 and pole piece 11 in pivotal relationship, the spring 19 is secured to the armature by means of the rivets 30 and the spring is tensioned along the portion 15 at the end nearest the pole piece 11, away from the armature 14.

Each of the terminals 16, 17 and 18 is provided with an upwardly extending leg such as 35 which is provided near its extremity with an embossed contact 43 adapted to be engaged by the spring 19. The terminals 16, 17 and 18 are also provided with wire connecting portions, such as 37 (Fig. 3), whereby external wire connections may be soldered thereto. In order to fasten the terminals 16, 17 and 18 to the base member 10 downwardly extending projections, such as 39 and 40 (Fig. 3) are provided which are inserted through holes provided therefor in the base member 10 and are bent over, as shown in Fig. 3, to clamp the terminals to the base 10.

The spring member 19 on the armature 14, which is tensioned away from the pivotal end of the armature along the portion 15 (Fig. 1), bears against the embossed contact in the terminal 16. With the tension of the spring 19 in this direction the free end of the armature 14 is resiliently held away from associated pole piece 12 to maintain the free end of the spring member 19 against the embossed contact in the terminal 17. Accordingly, any external circuit which is soldered to the terminals 16 and 17 is completed through the spring member 19, when the coil 13 of the electro-magnet is in a deenergized condition. When the coil 13 of the electro-magnet relay is in an energized condition, a magnetic circuit is completed through the core 20, the pole pieces 11 and 12, and the armature 14, whereupon the armature will pivot on the pole piece 11 and be attracted to the pole piece 12. By this movement of the armature the spring 19 will disengage terminal 17 and engage the embossed contact on the terminal 18, whereby the circuit which formerly included the spring 19 and the terminals 16 and 17 will now be opened and a new external circuit will be completed including the terminal 16, the spring 19, and the terminal 18. When the circuit of the coil 13 of the electro-magnetic relay is opened and the magnetic flux in the core 20 dies down, the tension of the spring 15 will move the free end of the armature 14 away from the pole piece 12, thereby opening the circuit which included the terminal 16, spring 19, and terminal 18 and reclose the first-mentioned circuit through the terminal 17.

It will be noted that the sole means for preventing the armature 14 from being displaced from the pivotal portion of pole piece 11 is the spring 19 which is tensioned along the portion 15 thereof and bears against the terminal 16 at one end and bears against the terminal 17 at the other end. With this method of suspending the armature 14 it will be seen that the armature 14 together with its associated spring 19 may be readily removed manually by overcoming sufficient of the tension in the portion 15 of the spring 19 to permit removal of the armature and its spring from the lugs 28 and 29 in the pole piece 11 and from engagement with the terminals 16 and 17.

In the event that the armature 14 has any tendency to stick to the pole piece 12, due to the lag in the flux of the magnetic circuit, a screw or rivet of non-magnetic material may be secured 5 to the armature, in the well known manner, to prevent the armature from actually contacting the pole piece 12.

The tension on spring 19 may be adjusted so that a weaker or a stronger magnetic flux would 10 be required to move the armature by slightly bending the upwardly extending leg, such as 35, of the terminal 16. Furthermore, the stroke of the armature 14 may be adjusted by slightly bending the upwardly extending leg, such as 35, 15 of the terminal 17.

In view of the foregoing it is apparent that an improved electro-magnetic relay is provided in which the coil and the pole pieces for supporting it, and the terminals for external electrical circuits 20 are all mounted upon a base of insulating material. Furthermore, it is also apparent that an improved method of retaining the armature in pivotal engagement by the same spring through which the electrical circuits may be 25 controlled, while still permitting manual removal of the armature and its associated spring without the use of tools.

Having described the invention, what is considered to be new and is desired to be protected by Letters Patent will be set forth in the following claims:

What is claimed is:

1. In a circuit controlling device, a base member, a pair of pole pieces secured to said base member, a core having a winding thereon supported by said pole pieces, an armature pivotally supported at one end thereof on one of said pole pieces and extending parallel to said core to permit engagement with the other of said pole pieces 35 when said core winding is energized, a spring member secured to said armature and having its ends extending beyond the ends of said armature, a first contact member secured to said base engaged by the end of said spring which extends 40 beyond the free end of said armature when said armature engages the said other pole piece, and a second contact member slidably engaged by the end of said spring which extends beyond the pivoted end of said armature whereby an electrical 45 circuit is completed between said contact members through said spring when said armature engages said other pole piece, said second contact member also providing a slidable contact to permit the removal of said armature from said device without the use of tools to permanently interrupt the circuit including said contacts.

2. In a circuit controlling device, a base, an electromagnetic device mounted on said base, an armature for said device removable therefrom 60 without tools, a plurality of terminals secured to said base, and a leaf spring secured to said armature tensioned at one end thereof to engage a first one of said terminals and thereby apply a restoring force to said armature, said spring 65 member at the other end thereof extending beyond the free end of said armature to engage a second one of said terminals when said armature is in a restored position and to engage a third one of said terminals when said electromagnetic 70 device attracts said armature, the first one of said terminals and said spring providing a slideable contact therebetween during movement of said armature either responsive to the operation of said device or responsive to the manual removal of said armature from said device.

3. In a relay, a base of insulating material, an electromagnetic device mounted on said base including an armature manually removable without the use of tools, a plurality of terminals secured to said base, and a leaf spring member secured to said armature tensioned at one end thereof to engage one of said terminals, said spring member at the other end thereof extending beyond the free end of said armature to engage a second one of said terminals when the 10 armature is in a restored position and to engage a third one of said terminals when said electromagnetic device overcomes said restoring force applied to said armature, said spring member by its resiliency acting as the sole means preventing the accidental removal of said armature and applying a restoring force to said armature.

4. In a relay mechanism, a flat base, a heel piece and a pole piece secured to said base, a coil mounted therebetween parallel to said base, 20 an armature removably mounted on said heel piece to rotate about an axis vertical to said base to engage said pole piece responsive to energization of said coil, a flat spring secured to said armature between said heel piece and said pole 25 piece and extending beyond the ends of said armature, and a pair of terminals secured to said base, one end of said spring engaging one of said terminals, the other end of said spring slidably engaging the other of said terminals and 30 tensioned to provide the sole force for maintaining said armature in position on said heel piece while permitting manual removal therefrom solely by overcoming the tension of said spring.

5. In a circuit controlling device, an electromagnet including an armature removable therefrom without the use of tools, a spring member attached to said armature, and contact members, one end of said spring member normally engaging one of said contact members, said spring movable responsive to the movement of the armature to engage a second of said contact members, the other end of said spring tensioned to normally engage a third of said contact members whereby said armature is maintained in position on said device and whereby manual effort to overcome the tension of said spring permits the removal of said armature from said device to thereby disconnect any electrical circuit including said spring and said third contact.

6. In a circuit controlling device, an electromagnet including an armature removable therefrom without the use of tools, a spring member attached to said armature, and contact members, one end of said spring member normally engaging one of said contact members, said spring movable responsive to the movement of the armature to engage a second of said contact members, the other end of said spring tensioned to slidably engage a third of said contact members whereby an electrical circuit including the third contact, the said spring and either the said first or the said second contact may be controlled by said electromagnet and whereby said electrical circuit may be disconnected manually without tools by overcoming the tension of said spring and removing the armature from said device.

MARTIN L. NELSON.
